HOSE REELING APPARATUS

**Earnest E. Martin, Pasadena, Calif., assignor, by
mesne assignments, to John Wood Manufacturing Company, Inc., New York, N. Y., a corporation of Delaware**

Application February 28, 1949, Serial No. 78,757

18 Claims. (Cl. 242—107)

1

This invention relates generally to improved hose reeling apparatus of the type adapted for automatic retraction or take-up of a hose after its manual withdrawal.

A major object of the invention is to provide a hose winding drum automatically operable, through movement of the shaft about which it is carried, to wind the hose in response to axial displacement of the drum. Preferably, I employ means adapted to rotate the shaft upon axial movement of the drum, and I transmit such rotation to the drum by in effect keying it to the shaft. To assure automatic return to a predetermined wound condition, the drum is normally urged in a hose winding axial direction, as by gravity, yielding means, or both.

An additional object of the invention is to provide means operable to transmit axial displacement of a drum into its hose reeling rotation, and vice versa, by the winding and unwinding of a flexible member, such as a cable, connected to the drum. In the preferred form of the invention, the drum is normally urged toward a first axial position, and the spindle is rotatable, upon withdrawal of the hose, to wind the cable and axially displace the drum. When the hose is then released, axial movement of the drum to its normal position unwinds the cable to rotate the spindle in an opposite direction and, through the spindle, effect hose reeling rotation of the drum.

Motion may be transmitted between the spindle and drum by movement of the drum carrying shaft and a pair of engaging gears. Preferably, I employ a stationary bevel gear, and a rotating and revolving bevel gear engaging the stationary gear and carrying the spindle.

The above and further features and objects of the present invention will be better understood from the following detailed description of the typical embodiment illustrated in the accompanying drawing, in which:

Fig. 1 is a side elevation of apparatus embodying the invention and especially adapted for the dispensing of water and air at a service station,

Fig. 2 is an enlarged vertical section through the apparatus of Fig. 1; and

Fig. 3 is an enlarged fragmentary vertical section taken on line 3—3 of Fig. 2.

The illustrated water and air dispensing apparatus is contained within a vertically extending tubular housing 10, having bottom and top walls 11 and 12, respectively, and divided internally by transverse partition 13 into upper and lower spaces 14 and 15. Each of these spaces is

2

closed at one side by a door 16, having a hose-passing opening 17, about which are carried rollers 18 adapted to permit withdrawal and retraction of the corresponding hose with minimum friction. Spaces 14 and 15 contain substantially identical reeling mechanism, generally indicated at 19, for permitting manual withdrawal and effecting automatic take-up of water and air hoses 20 and 21, respectively. Each of these hoses is provided with an enlargement 22 at the outside of the housing adapted to limit retraction of the hose by engagement with rollers 18. Hose 20 carries the usual water dispensing valve 23, and hose 21 is provided with the air chuck and control valve assembly 24.

Each reeling mechanism 19 includes a vertically extending shaft 25 rotatably mounted between a lower bracket 26 and an upper bracket 27, which, as will appear later, serves also as a stationary gear. Bracket 27 is rigidly secured, as by screws 28, to the upper wall of the space, and presents an opening 29 in its bottom surface, within which the reduced upper end 30 of shaft 25 is journaled.

25 Hose winding drums 31, carried about the lower portions 36 of shafts 25, respectively, each contain an integrally formed annular weight 32 normally urging the drum downwardly. The drums may present external helical grooves 35 within which the hoses 20 and 21 are windable. Bearing member 34 is rigidly carried within an axially extending central opening 35 in weight 32, and slidably engages the shaft to guide the drum for axial or vertical movement. The external surface of the lower portion 36 of shaft 25 and the internal surface of member 34 are of corresponding non-circular configuration to key the shaft and drum for rotation together, while permitting the defined axial movement of the drum. Spiral spring 37 is disposed between flange 38 of the shaft and drum weight 32 to cooperate with the weight in normally urging the drum downwardly along the shaft. It is, of course, contemplated that, in certain installations, it may be desirable to delete the spring and employ the weight alone to lower the drum. Similarly, the spring may, if desired, supply the major force, in which case a relatively light frame member can be substituted for weight 32.

50 Above flange 38, shaft 25 carries a transversely extending secondary shaft 39. At either side of shaft 25, shaft 39 rotatably carries a bevel gear 40, having an outwardly extending hub or spindle portion 41. Each of these spindle portions has a spiral groove 42 extending about and along its

outer surface. A cable 43 is connected to each spindle at 44 and is windable within groove 42 by rotation of the gear and spindle unit. The opposite end of each cable is secured to weight 32, as by an eye 56, so that winding of the cable about the spindle effects upward movement of the drum along shaft 25. The gears are retained against outward displacement from shaft 39 by thrust washers 45 and nuts 46. The outer surface of bracket 27 forms a horizontally extending stationary bevel gear 47 engaging gears 40 to require rotation of gears 40 about shaft 39 in response to bodily revolution of the gears about shaft 25, and to similarly require such bodily revolution upon rotation of the gears about shaft 39.

Compressed air is supplied through inlet 48, which communicates with flexible spiral tube 49 through swivel connection 50 of known type. Flexible tube 49 connects with a short outwardly extending conduit 51, which leads directly into hose 21 to permit dispensing of air through chuck 24. Similarly, water is supplied to hose 20 through inlet 52, swivel connection 53, a flexible spiral tube corresponding to tube 49 (not shown), and outwardly extending conduit 54.

In use, drums 31 are normally urged downwardly by spring 37 and the effect of gravity on weight 32 to the position in which the upper or water hose drum is illustrated in Fig. 2. Withdrawal of either hose through its hose-passing opening rotates the corresponding drum 31 and shaft 25, and causes gears 40 to bodily revolve about the axis of shaft 25. Engagement of gears 40 with stationary gear 47 during such revolving motion causes gears 40 to simultaneously rotate in opposite directions about shaft 39 and wind cables 43 about spindle portions 41. Winding of the cables retracts drum 31 upwardly against the influence of gravity on the weight and against the force of spring 37. The lower or air hose is illustrated in Fig. 2 as thus partially withdrawn and with its drum moved upwardly. When a hose is released after such manual withdrawal from the housing, the spring and weight immediately displace the drum downwardly toward the normal position, and, as a result of that movement, unwind cables 43 from their respective gears 40. The resultant rotation of gears 40 about shaft 39 causes their bodily revolution about stationary gear 47 in a hose winding direction. As will be understood, the revolving motion is transmitted through the two shafts to drum 31, resulting in automatic take-up or retraction of the hose to the normal condition.

I claim:

1. Hose reeling apparatus, comprising a rotatable shaft, a rotatable winding drum disposed about said shaft, said drum being axially movable along said shaft, and means operable by rotation of said shaft to rotate said drum in response to axial displacement of the drum.

2. Hose reeling apparatus, comprising a rotatable shaft of non-circular cross-sectional configuration, a hose winding drum having an axial opening of corresponding sectional configuration and disposed about said shaft in predetermined angular relation thereto, said drum being axially movable along said shaft, and means operable to rotate said shaft and thereby said drum in response to axial displacement of the drum.

3. Hose reeling apparatus, comprising a movable shaft, a rotatable and axially movable hose winding drum disposed about said shaft, and means operable by movement of said shaft to rotate said drum in response to axial displace-

ment of the drum, said last mentioned means including a flexible member connected to said drum and means for winding said flexible member.

5. Hose reeling apparatus, comprising a hose winding drum mounted for both rotation and axial movement, and means operable to rotate said drum in response to axial movement thereof, said means including a flexible member extending axially beyond said drum.

10 6. Hose reeling apparatus, comprising a hose winding drum mounted for both rotation and axial movement, and means operable to rotate said drum in response to axial movement thereof, said means including a flexible member connected to and extending axially beyond said drum and means for winding said flexible member.

15 7. Hose reeling apparatus, comprising a hose winding drum mounted for both rotational and axial movement, a flexible member connected to said drum and extending therefrom in a first axial direction, and means operable by said flexible member to rotate said drum in response to movement of the drum in the opposite axial direction.

20 8. Hose reeling apparatus, comprising a hose winding drum mounted for both rotational and axial movement, a flexible member connected to said drum and extending therefrom in a first axial direction, and means operable by said flexible member to rotate said drum in response to movement of the drum in the opposite axial direction, said means including a rotatable spindle about which said flexible member is windable and adapted to be rotated by the unwinding of said member upon drum movement in said opposite direction.

25 9. Hose reeling apparatus, comprising a rotatable shaft, a hose winding drum carried about said shaft and angularly keyed thereto for rotation therewith, said drum being axially movable along said shaft, a flexible member connected to said drum and extending therefrom in a first axial direction, and means operable by said flexible member to rotate said shaft and thereby to rotate said drum in response to movement of the drum in the opposite axial direction.

30 10. Hose reeling apparatus, comprising a rotatable shaft, a hose winding drum carried about said shaft and angularly keyed thereto for rotation therewith, said drum being axially movable along said shaft, a flexible member connected to said drum and extending therefrom in a first axial direction, and means operable by said flexible member to rotate said shaft and thereby to rotate said drum in response to movement of the drum in the opposite axial direction, said means including a rotatable spindle about which said flexible member is windable and adapted to be rotated by the unwinding of said member upon drum movement in said opposite direction.

35 11. Hose reeling apparatus, comprising a rotatable shaft, a hose winding drum carried about said shaft and angularly keyed thereto for rotation therewith, said drum being axially movable along said shaft, a flexible member connected to said drum and extending therefrom in a first axial direction, means operable by said flexible member to rotate said shaft and thereby to rotate said drum in response to movement of the drum in the opposite axial direction, said means including a rotatable spindle about which said flexible member is windable and adapted to be rotated by the unwinding of said member upon drum

movement in said opposite direction, and including means mounting said spindle for rotation about an axis fixed relative to said shaft.

11. Hose reeling apparatus, comprising a hose winding drum mounted for both rotational and axial movement, a flexible member connected to said drum and extending therefrom in a first axial direction, means operable by said flexible member to rotate said drum in response to movement of the drum in the opposite axial direction, said means including a rotatable spindle about which said flexible member is windable and adapted to be rotated by the unwinding of said member upon drum movement in said opposite direction, means mounting said spindle for rotation about an axis fixed relative to said shaft, a gear rotatable with said spindle about said axis, and a second and stationary gear engageable by said rotatable gear to cause said rotatable gear to bodily revolve about the axis of the drum in response to the unwinding of said flexible member.

12. Hose reeling apparatus, comprising a rotatable shaft, a hose winding drum carried about said shaft and angularly beeyed thereto for rotation therewith, said drum being axially movable along said shaft, a pair of flexible members connected to said drum and extending therefrom in a first axial direction, a second shaft extending transversely through said first mentioned shaft and rigidly carried thereby, a pair of inwardly facing bevel gears rotatably carried by said second shaft at either side of said first mentioned shaft, each of said gears having a spindle projection to which one of said flexible members is secured and about which said member is windable, said spindles and their associated gears being rotatable about said second shaft by the unwinding of said flexible members upon movement of said drum in the reverse direction of said first axial direction, and a stationary bevel gear engageable by said rotatable gears to cause said rotatable gears to bodily revolve when rotated about said second shaft, said revolving motion being transmitted through both of said shafts to said drum to thereby cause drum rotation in response to axial displacement of the drum.

13. Hose reeling apparatus, comprising a movable shaft, a rotatable and axially movable hose winding drum disposed about said shaft and movable relative thereto, and means operable by

movement of said shaft to rotate the drum in response to axial displacement of the drum.

14. Hose reeling apparatus, comprising a rotatable shaft, a rotatable and axially movable hose winding drum disposed about said shaft and movable relative thereto, and means operable by rotation of said shaft to rotate the drum in response to axial displacement of the drum.

15. Hose reeling apparatus, comprising a rotatable shaft, a rotatable hose winding drum disposed about said shaft and axially movable relative thereto, means keying said shaft and drum for rotation together, and means operable to rotate said shaft and thereby said drum in response to axial displacement of the drum.

16. Hose reeling apparatus, comprising a movable solid shaft, a rotatable and axially movable hose winding drum disposed about said shaft, and means operable by movement of said shaft to rotate the drum in response to axial displacement thereof.

17. Hose reeling apparatus, comprising a rotatable solid shaft, a rotatable and axially movable hose winding drum disposed about said shaft, and means operable by rotation of said shaft to rotate the drum in response to axial displacement thereof.

18. Hose reeling apparatus, comprising a hose winding drum mounted for both rotation and axial movement, a flexible member connected to the drum, and means operable by said flexible member to rotate the drum in response to axial movement thereof.
